APPARATUS FOR SPINNING SOLUTIONS
OF HIGH POLYMERS

Pierre Salé, A La Demi-Lune, and Joseph A. Trillat, Lyon, France, assignors to Societe Rhodiaca, Paris, France, a French company

Application June 3, 1949, Serial No. 96,882
In France February 5, 1949

5 Claims. (Cl. 18—8)

1

It is customary in the spinning of solutions of high polymers, such as for example cellulose derivatives (cellulose xanthogenate and esters or ethers of cellulose), or synthetic polymers (polyvinyl derivatives, polyamidine derivatives, etc.) to protect the apertures of spinnerets by means of a filter called "garniture."

The present invention relates to a unit or device for spinning solutions of high polymers, which renders it possible to obtain surprisingly interesting results from a technical point of view in so far as it extends, in a manner unknown up to date, the period of technical use of a spinneret which can be used now for several months without alteration, even with interruptions of several days.

This remarkable result, which is of great economic and technical interest, has been attained by utilizing in the spinning of high-polymer solutions a unit comprising:

A spinneret plate which consists of rigid metal and is provided with extrusion orifices having a cross section at the inlet which is at least fifty times larger than the cross section at the outlet;

Arranged directly above said plate and in contact with it on a surface comprising all of the orifices and in such a manner that the spinning solution could not pass around without penetrating it is a "special filter" comprising at least one fabric formed of threads having a substantially cylindrical cross-section, in which the average width of the gaps left between the threads by their crossing is smaller than the cross-section of the extrusion apertures at their outlet;

A device for preliminary filtration which may contain at least one fabric similar to that mentioned above and which should be separated from the "special filter" by a space which allows the solution issued at all points of the preliminary filter to reach any of the extrusion orifices.

Numerous embodiments may be used in obtaining such units, with regard to the nature of the various elements or their assembling.

As to the nature of said elements, the spinneret plate may advantageously consist of unoxidizable steel, the thickness of which is determined by the bending stresses which it has to undergo as a function of its diameter, and the pressure of extrusion. It may be provided with holes of any desired shape. It has been found that in order to obtain a sufficient spinning time before clogging it is necessary that the cross section of the orifices at the inlet be equal to at least 50 times the cross section at the outlet. Moreover, this proportion may with advantage attain

2

100—200 or even 10,000 to 80,000. The tissue forming the special filter may consist of substantially cylindrical threads of any kind: bronze, nickel, synthetic materials, particularly superpolyamides or vinyl polymers and analogous materials. Tightening of the threads, which is necessary to obtain very fine interstices, may be attained either directly or by means of an after-treatment causing contraction. It has been found 10 that in order to obtain an improvement of the spinning conditions, it is necessary to use at least one of these tissues, which may have for example a plain weave or satin weave. However, it is of advantage to use several layers which are 15 eventually assembled by "welding" the edges, gluing or setting, the number of the layers being limited only by the resulting increase of pressure. In all cases in which several layers of fabric are present, they may comprise layers 20 which are of different types with regard to fineness or with regard to weave. The device for preliminary filtration may also comprise one or more layers of analogous fabrics eventually assembled, welded or set together, or fabrics of different 25 weave or tightness may be used. This device may also comprise grids for detaining coarse impurities, fabrics of the usual type, sheets of natural or artificial fibers which are carded or not, with separating spaces between the various materials or filter layers, etc.

30 As far as the assembling is concerned, there are three essential conditions to be met by the device used, i. e. the following: (1) The "special filter" should be in direct contact with the spinneret plate on a surface comprising all of the orifices; (2) the solution should not be able to avoid this filter and particularly it should not infiltrate through the edges toward the holes or orifices of the spinneret; and finally, (3) it is necessary 35 to provide between the "special filter" and the device for preliminary filtration a space which corresponds to the description set forth above. Each of these conditions may be effected by any suitable means, some of which are disclosed hereinafter by way of example. The first condition 40 may be realized, for example, by using very even tissues such as can be obtained by rolling, calendering or ironing or (in the case of synthetic filaments) by setting the tissue or tissues and subjecting them subsequently to a contracting treatment in order to stretch them. The second condition 45 may be met, for example, either by welding the periphery of the special filter to the front surface of the spinneret plate or by pressing said periphery toward said plate by means of a system 50 55

of joints. A convenient means for realizing the third condition consists in interposing between the "special filter" and the device for preliminary filtration a circular member supporting a grid or perforated rigid plate, which is held in spaced position by means of studs or braces, and thereby supports the preliminary filtration unit.

It will be understood that there are very many possible embodiments of the units according to the invention, and the example stated below should not be considered limitative in any respect, i. e. neither with regard to the selection nor with regard to the arrangement of the various parts forming the equipment according to the invention. This example demonstrates particularly clearly the considerable technical progress obtainable in the spinning of high polymers by the use of the device according to the invention, since it is possible thereby to reduce the frequency of changing the spinnerets to an extent not known up to date.

Example

A 24% solution of cellulose acetate in acetone is extruded in a known manner from a dry spinning cell in order to obtain a thread of 100 deniers-18 filaments.

A unit suitable for carrying out the invention is illustrated in the accompanying drawing, in which

Fig. 1 is a central vertical section through the unit; and

Fig. 2 is a plan view thereof.

In the drawing, 1 designates a nut in threaded engagement with an exteriorly threaded member 11 forming the end portion of conduit 2 which supplies the spinning solution. A spinneret plate 3 of unoxidizable steel of a thickness of 2 mm. is threaded into said nut and is provided with 18 extrusion apertures 4, each of which has a cross-section of 0.005 mm.² at the outlet and 12.5 mm.² at the inlet. Directly on said plate is placed a disk 5, the diameter of which is equal to that of the spinneret plate and which comprises two previously calendered bronze gauzes in the surface of which the interstices between the threads have a width of 0.003 mm.², and two layers of a superpolyamide fiber satin, in which the average width of the interstices is 0.001 mm.². The edges of these four layers are glued on their entire circumference by means of a superpolyamide varnish. Member 6 is a metal-plastic ring of 3 mm. thickness, the compression of which ensures the lateral tightness of the unit in such a manner that the solution cannot pass around member 5 and is compelled to traverse said member. A rigid plate 7 of unoxidizable steel of 3 mm. thickness is provided with apertures in communication with the separating space 8. Above the plate 7 there is a second disk 9 which is formed of a bronze gauze and a layer of superpolyamide fiber satin similar to those in the member 5, which are set by means of brass. Member 10 is a preformed plate of plastic material, which simultaneously forms a joint and ensures tightness between the unit members 1, 10 and 11, the latter being as above stated the end portion of the conduit supplying the spinning solution. Above the preliminary filtration unit is a filtering layer 12 of a known and customary type.

According to a modified embodiment of this device, the spinneret plate may be held in the nut 1 by means of a shoulder instead of the threading. According to still another modifica-

tion, a threaded member having a large central opening may be interposed between the perforated plate 10 and the coupling of conduit 11 and such member would provide for fixing and compression of the various members even before the unit is mounted on the supply tube of the spinning solution.

The number of spinnerets to be put in action in order to correctly start a spinning frame by means of the units thus constructed is 6% lower than that necessary in the use of the usual spinnerets. The period of spinning before it becomes necessary to change the spinnerets is 20 to 100 times higher compared with a frame provided with a usual type of spinnerets.

It will be understood by those skilled in the art that the present invention is not limited to the specific details described or shown and may be carried out with various modifications. Thus, soldering may be used instead of welding and other varnishes may be used instead of the superpolyamide varnish for connecting the filter layers at their circumference. Furthermore, the thickness of ring 6 shown in the drawing may be less than 3 mm., although it must have a thickness holding the device for preliminary filtration at a distance of at least 1 mm. from the special filter. These and other modifications may be made without departing from the scope of the invention as defined in the appended claims.

We claim as our invention:

1. A device for spinning a solution of high polymers, including a spinneret plate of rigid metal provided with extrusion orifices having a cross-sectional area at the inlet equal to at least 50 times the cross-sectional area at the outlet, comprising, in combination, a spinneret plate filter placed on said plate, said filter being in contact with said plate over its entire surface and covering all of said orifices, said spinneret plate filter comprising at least one fabric formed of filaments of synthetic resinous material, said filaments having a substantially circular cross-section and cylindrical shape, said fabric containing at least 10,000 interstices per square centimeter between the thread crossings, the average area of said interstices being smaller than the cross-sectional area at the outlet end of said extrusion orifices and being equal to at most 0.003 square millimeter, and, spaced from the spinneret plate filter and separated therefrom by a hollow space of at least 1 mm. thickness, a preliminary filter containing at least one fabric formed of filaments of synthetic resinous material, in order to permit the solution issuing from all points of the preliminary filter, to reach any of the extrusion orifices, said filaments having a substantially circular cross-section and cylindrical shape, said fabric containing at least 10,000 interstices per square centimeter between the thread crossings, the average area of said interstices being smaller than the cross-sectional area at the outlet end of said extrusion orifices and being equal to at most 0.003 square millimeter.

2. A device of the type claimed in claim 1, in which the spinneret plate filter consists of two calendered bronze gauzes, in which the average area of interstices amounts to about 0.003 mm.² and two layers of superpolyamide fiber satin, in which the average area of the interstices is 0.001 mm.², the edges of these four layers being glued on their entire circumference.

3. A unit for spinning solutions of high polymers, in which a device as claimed in claim 1, 75 is tightly enclosed in a tubular member having

a cylindrical inner surface and in which the spinneret plate filter consists of two calendered bronze gauzes, in which the average area of interstices amounts to about 0.003 mm.² and two layers of superpolyamide fiber satin, in which the average area of the interstices is 0.001 mm.², the edges of these four layers being glued on their entire circumference.

4. A device for spinning a solution of high polymers, including a spinneret plate of rigid metal provided with extrusion orifices having a cross-sectional area at the inlet equal to at least 50 times the cross-sectional area at the outlet, comprising, in combination, a spinneret plate filter placed on said plate, said filter being in contact with said plate over its entire surface and covering all of said orifices, said spinneret plate filter comprising at least one fabric formed of filaments of synthetic resinous material, said filaments having a substantially circular cross-section and cylindrical shape, said fabric containing at least 10,000 interstices per square centimeter between the thread crossings, the average area of said interstices being smaller than the cross-sectional area at the outlet end of said extrusion orifices and being equal to at most 0.003 square millimeter, and, spaced from the spinneret plate filter and separated therefrom by a hollow space of 1-3 mm. thickness, a preliminary filter containing at least one fabric formed of filaments of synthetic resinous material, in order to permit the solution issuing from all points of the preliminary filter, to reach any of the extrusion orifices, said filaments having a substantially circular cross-section and cylindrical shape, said fabric containing at least 10,000 interstices per square centimeter between the thread crossings, the average area of said interstices being smaller than the cross-sectional area at the outlet end of said extrusion orifices

and being equal to at most 0.003 square millimeter.

5. A device for spinning solutions of high polymers, in which the solution is forced through a preliminary filter which contains at least one fabric formed of filaments of synthetic resinous material, said filaments having a substantially circular cross-section and cylindrical shape, said fabric containing at least 10,000 interstices per square centimeter between the thread crossings, the average area of said interstices being equal to at most 0.003 square millimeter and then through a spinneret plate filter spaced from the preliminary filter and separated from the latter by a hollow space and a perforated plate supporting the preliminary filter substantially on its entire surface, said spinneret plate filter containing at least one fabric formed of filaments of synthetic resinous material, said filaments having a substantially circular cross-section and cylindrical shape, said fabric containing at least 10,000 interstices per square centimeter between the thread crossings, the average area of said interstices being equal to at most 0.003 square millimeter.
